UNITED STATES PATENT OFFICE.

GEORGE W. LEVI, OF LOUISVILLE, KENTUCKY, ASSIGNOR OF ONE-HALF
TO M. J. DUFFY AND LOUIS KOSIAL, OF SAME PLACE.

FIRE-ESCAPE.

SPECIFICATION forming part of Letters Patent No. 252,839, dated January 24, 1882.

Application filed October 24, 1881. (No model.)

To all whom it may concern:

Be it known that I, GEORGE WASHINGTON LEVI, of Louisville, in the county of Jefferson, and State of Kentucky, have invented certain 5 new and useful Improvements in Fire-Escapes; and I do hereby declare that the following is a full, clear, and exact description thereof, reference being had to the accompanying drawings, and to the letters of reference marked 10 thereon, which form part of this specification, in which—

Figure 1 is a front and Fig. 2 a side elevation of our device, showing its application and method of attachment.

15 The main object I have in view is to provide a fire-escape which from its capability of resisting heat will afford a sure means of exit from a burning building.

My invention consists in such combination 20 and arrangement of devices as will be hereinafter more fully set forth.

To enable others skilled in the art to which my invention pertains to avail themselves of its benefits, I will now proceed to describe its 25 construction and use.

A represents a pipe of suitable size, which connects with the company's main pipe.

B B represent branch pipes, which are preferably joined at bottom and top, and the connection of these pipes at their lower ends is 30 united to the pipe A, thus admitting of a continuous flow of water through them, as will be presently more fully seen. The stand-pipe A and also the connecting-joint at the upper ends 35 of the pipes B B are provided with hose-connections a a.

C C are the cross-bars or rounds of the ladder, which are also composed of pipe and suitably connected with the branch pipes or sides 40 of the ladder to admit of a free flow of water through them.

E E represent platforms, which are intended to both support the ladders at each story of the building and to afford a safe and convenient 45 means of reaching it from the windows thereof.

b b are safety guards or railings around these platforms; and e e, small hose attachments on the pipes B B, which are purposely located in

front of each row of windows, so that by any person standing on any one of the platforms, 50 a hose, or a number of them, can quickly be brought into requisition.

d d represent suitable attachments to the branch pipes, by means of which a block and tackle may be secured for raising and lowering 55 large hose, &c.

It will now be observed that as soon as water is admitted to the stand-pipe there may not only be a free discharge from any of the hose attachments, but a rapid and continuous circulation or flow through the branch pipes B B and rounds C C, thus effectually preventing them from becoming impaired by reason of the heat or too warm to be used as an escape from the burning building.

I am aware that escape-ladders have been made from piping so connected that a current of water can be forced through the same, and therefore do not claim such, broadly, as my invention.

Having thus fully described my invention, what I claim as new, and desire to secure by Letters Patent, is—

1. In a fire-escape ladder, the combination of branch pipes B B, cross-pipes C C, hose-connections a a, platform E E, and stand-pipe A, all in the manner and for the purpose set forth.

2. The combination, in a fire-escape ladder, of the branch pipes B B, having tackle attachments d d, and platforms E E, with railings b b, substantially as and for the purpose set forth.

3. The within-described fire-escape ladder, consisting of the branch pipes B B, cross-pipes C C, stand-pipe A, platforms E E, and tackle attachments d d, all substantially as and for the purpose set forth.

In testimony that I claim the foregoing as my own I affix my signature in presence of 90 two witnesses.

GEORGE WASHINGTON LEVI.

Witnesses:

LOUIS KOSIAL,
LEE CHAMBERS.
